UNITED STATES PATENT OFFICE.

NORMAN R. SMITH, OF SEATTLE, WASHINGTON.

STEAM-TURBINE.

No. 812,693.

Specification of Letters Patent.

Patented Feb. 13, 1906.

Application filed June 8, 1905. Serial No. 264,354.

To all whom it may concern:

Be it known that I, NORMAN R. SMITH, a citizen of the United States, and a resident of the city of Seattle, county of King, and State of Washington, have invented certain new and useful Improvements in Steam-Turbines, of which the following is a specification.

My invention relates to improvements in gaseous-impact motors, such as are typified by steam-turbines.

The object of my invention is to improve and simplify said devices.

The scope of my invention will be defined in the claims.

15 The drawings accompanying herewith illustrate my invention in the form which is now preferred by me.

Figure 1 is an elevation in which one-half of the device is mostly broken away in order 20 to better show the disposition of the internal parts. Fig. 2 is a sectional elevation taken parallel with the axis. Fig. 3 is a detail section taken lengthwise one of the jets. Fig. 4 is a diagrammatic section taken lengthwise 25 one of the cups or pockets. Figs. 5 and 6 are diagrams illustrating the transverse form of one of said pockets at points in its length represented by the correspondingly-numbered lines of Fig. 4.

30 One object which I have attempted to secure by my invention is to reduce the rotative speed to such a degree as to make the motor applicable to drive the average mechanism without requiring special speed-reducing devices.

Another object is to produce a reversible turbine and also a design which will be cheap in its first cost.

My invention comprises two principal rotative parts A and B, which are essentially alike in construction, the parts when a reversible turbine is wanted being adapted to be either one clamped to the shaft and the other held against turning, the direction of rotation 45 being dependent upon which part is secured to the shaft. Each of these principal parts A and B is of the general form of a disk having pockets or cups a b of special form in one face, the cupped faces of the two disks 50 being opposed and in close contact. These disks are loosely journaled upon the shaft C;

but means are provided whereby they may either one be held to turn with the shaft or held against turning, as desired.

The cups or pockets a and b are arranged 55 in series of spirals, as is clearly shown in Fig. 1, the spirals on one disk being opposite in direction to those upon the other disk. This is clearly shown by that portion of Fig. 1 which shows the outlines of the pockets dotted. The lines composed of dashes outline the pockets in the disk A, while the dotted lines outline the pockets in disk B. These lines of one disk cross the corresponding lines of the other disk at an angle. The general 60 form of the individual pockets is best shown by the diagrams of Figs. 4, 5, and 6. Fig. 4 shows the outline of a pocket on a central longitudinal plane, while Figs. 5 and 6 show by their various curves the outlines of a 65 pocket taken upon the correspondingly-numbered lines of Fig. 4—that is, the lines 1 2 3 4, &c., of Figs. 5 and 6 show the shape 70 of the surface of the pocket at points 1 2 3 4, &c., of Fig. 4. These curves are 75 given with as near an approximation to the truth and my conception of the form which is most desirable as I can now give. I do not, however, wish to be understood as saying that these forms must be exactly followed, 80 as I am aware that such is not the case. They, however, represent my present conception of the best form for these cups. As will be seen by referring to that portion of Fig. 1 which shows these cups dotted, there 85 are an unequal number of cups, in the two disks, one being divided thereby into preferably an even number of angular segments and the other into an odd number of segments. I have shown the disk A as having 90 twelve segments and the disk B as having thirteen. At the center each disk is provided with a chamber D, from which the steam is discharged into the innermost of the cups a and b. These chambers in the two disks are 95 connected by segment-slots d of such size that communication between the two chambers is not interfered with by the rotation of the disks. The steam is supplied to said chambers through one of the annular passages d', surrounding the sleeves A' and B', from the steam-supply pipe S.

The steam is discharged from the chambers D through a series of nozzles E so located in each disk as to discharge into the innermost cups of the opposite disk. The cups 5 are inclined oppositely in the respective disks and the nozzles are also inclined oppositely or so that they discharge against the end surface of the cups of the opposite disk. The jet of steam discharging into the innermost 10 cup is deflected backward and outward toward the face of the disk and by reason of the relative positions of the cups in the two disks into one of the cups of the other disk. This action will proceed from one cup to another 15 and alternating from one disk to another until the steam is discharged through peripheral ports e.

In order to control the revolution of the disks, I provide friction-clutches, by which 20 either may be secured to the shaft, and also brakes, by which either may be held against turning. The manner of constructing these is immaterial. I have shown the sleeves A' and B' as being coned and engageable by a 25 corresponding coned member T, which is mounted upon the shaft C by a key and feather, so that it may slide, but must turn with the shaft. This is controlled by a lever G. The brakes shown consist of shoes H, 30 bearing upon the rim of the disks and operated by levers I. By holding one disk and clamping the other to the shaft the shaft is turned in one direction. By reversing this order the shaft is turned in the opposite direction. 35

The disks are preferably surrounded by an exhaust-casing L, which entirely incloses them, and the exhaust-steam is led away through a pipe L'. To prevent leakage about 40 the sleeves A' and B', I have shown grooves J, which are connected with the exhaust-chamber by drip-passages.

By reason of the shape and arrangement of the cups upon two opposed disks the energy 45 of the steam is gradually extracted and the speed of the turbine is kept within reasonable and practicable limits. It may therefore be run direct-connected with many devices which would require speed-reducing devices 50 if operated by other turbines.

I have in the drawings shown the shape of cups or buckets which I now think is best, but am aware that departures from this shape 55 may be made and yet obtain good results and possibly better. I do not, therefore, wish to be limited to the shape shown.

Having thus described my invention, what I claim, and desire to secure by Letters Patent, is—

60 1. A steam-turbine comprising two opposed disks having a plurality of series of

spirally-disposed cups or buckets formed in their opposed faces, and means for discharging steam into the inner cup of each series.

2. A steam-turbine comprising two opposed disks having a plurality of series of spirally-disposed cups or buckets formed in their opposed faces, means for discharging steam into the inner cup of each series, and means for securing either disk to the shaft 65 70 and for holding the other disk against turning.

3. A reversible steam-turbine comprising two disks mounted upon a common axis with faces in contact, said contacting faces having cups formed therein and disposed in a plurality of spirally-disposed series and means for injecting steam to the innermost of these cups, said cups being formed to deflect the steam in a direction which is a combination of a tangential and an axial direction and 75 into a cup upon the other disk.

4. A reversible steam-turbine comprising two disks mounted upon a common axis with faces in contact, said contacting faces having cups formed therein and disposed in a plurality of layers the successive cups of any series being at an increased distance from the center and means for injecting steam to the innermost cups of each series, said cups being formed to deflect the steam in a direction 85 which is a combination of a tangential and an axial direction and into a cup upon the other disk, and means for clamping said disks to their shaft and for holding them against turning, operated in alternate and opposite 90 95 relation.

5. A steam-turbine disk having cups in the face thereof arranged in a plurality of series the cups of each series being spirally disposed.

6. A steam-turbine disk having cups in its 100 face, said cups having a major axis and an inner surface sloping from the surface of the disk at one end of the major axis inward to a maximum depth at or near the other end of its major axis, said major axis extending substantially in a direction which is tangential from the deeper end of the cup. 105

7. A steam-turbine disk having cups in its face having their major axes substantially tangential and deepest at the inner ends of 110 said axes and sloping thence to the surface at the outer ends of said axes.

8. A steam-turbine disk having cups in its face arranged in a plurality of spirally-disposed series, said cups being deepest at their 115 ends toward the center in the direction of the spirals.

9. A steam-turbine comprising two disks mounted to turn with their faces in contact, each disk having cups in its contact-face arranged in a plurality of spirally-disposed series, said cups being deepest at their ends to- 120

ward the center in the direction of its spiral and the spirals of the two disks extending respectively in opposite directions.

10. A steam-turbine comprising two disks mounted to turn with their faces in contact, each disk having cups in its contact-face arranged in a plurality of spirally-disposed series, said cups being deepest at their ends toward the center in the direction of the spiral, the spirals of the two disks extending respec-

tively in opposite directions, and means for discharging jets of steam into the innermost cups of said series.

In testimony whereof I have hereunto affixed my signature, this 1st day of June, 1905, in the presence of two witnesses.

NORMAN R. SMITH.
